UNITED STATES PATENT OFFICE.

HENRY P. McBRIDE, OF CHICAGO, ILLINOIS.

INSULATING-JOINT.

1,102,775.

Specification of Letters Patent.

Patented July 7, 1914.

Application filed October 20, 1913. Serial No. 796,232.

To all whom it may concern:

Be it known that I, HENRY P. McBRIDE, a citizen of the United States, and a resident of the city of Chicago, county of Cook, and 5 State of Illinois, have invented certain new and useful Improvements in Insulating-Joints, of which the following is a specification.

My improvement relates to insulating 10 joints for electric fixtures.

The object of this improvement is to provide an insulating joint which incorporates a hickey with said joint and provides a means for easily connecting and disconnecting 15 electric wires in the fixtures.

Other objects will appear hereinafter.

The invention consists in the combinations and arrangements of parts hereinafter described and claimed.

20 The invention will be best understood by reference to the accompanying drawing forming a part of this specification, and in which—

Figure 1 is a vertical section of an insulating joint embodying my invention, and 25 illustrates its method of installation, Fig. 2 is a section of the same taken on line 2—2 in Fig. 1, Fig. 3 is a plan view of an insulating joint used to connect combination electric 30 and gas fixtures which embodies my invention, and Fig. 4 is a section of the same taken on line 4—4 in Fig. 3.

The preferred form of construction as 35 illustrated in the drawing comprises an annular insulating block 5 having a fixture connector embedded in its central portion and electrical wire connectors embedded in said block. In an insulating joint adapted for connecting electric fixtures, I employ 40 the form shown in Figs. 1 and 2 in which the fixture connector 6 is embedded in the insulating block 5. At the upper end of fixture connector 6 is a loop 7 which is provided with an insulating covering 8 around 45 its upper portion. The insulating material 8 engages the hoop end 9 of a connector 10 which is screw threaded on a ceiling plate 11, the latter being secured to the ceiling by means of conventional screws 12. The insulating material 8 on loop 7 is provided to 50 insulate the fixture support 6 from the supporting hook 9.

Threaded in the fixture connector 6 is the 55 upper end of an electric fixture 13 which is provided with conventional fixture wires 14 which lead upwardly and around the

upper edge of fixture connector 6 with their ends secured in wire connectors 15 one end of each of said fixture wires engaging a socket 16 in one of the electric connectors 15. The electric connectors 15 are preferably embedded in the insulating block but may be secured in the block 5 in suitable 60 openings in any approved manner.

In the periphery of the insulating block 5 are provided a plurality of recesses 17 which have openings leading therefrom to the connectors 15. Binding screws 18 are disposed in the openings in block 5 with their heads disposed in recesses 17 and their inner ends threaded in sockets 16 securely holding the fixture wires in said sockets. The connectors 15 are also provided with sockets 19 which are adapted to receive the line wires 20. The sockets 19 are provided with binding screws 18 fitted therein in the same manner as binding screws 18 are fitted in sockets 16. With this construction it will be seen that the line wires 20 may be easily 65 connected and disconnected when so desired thus doing away with the ordinary method of soldering the line wires and fixture wires at the insulating joint.

In the form shown in Figs. 3 and 4 the fixture wires are not led to the interior of the fixture connector. In this construction the insulating block 5 is provided with electrical wire connectors 15 and the latter are provided with sockets 16 and 19 for the reception of the line wires and fixture wires in the same manner as that shown in Figs. 1 and 2. In this form a pipe line connector 21 is embedded in the upper end of insulating block 5 and a fixture connector 22 embedded in the lower end of the insulating 70 block 5. Both of the connectors 21 and 22 are secured in the insulating block 5 in a manner to provide fluid tight joints therebetween. Connectors 21 and 22 are secured in insulating block 5 in the conventional 75 manner. The only new feature in this form is the provision of the wire connectors 15.

While I have illustrated and described the preferred forms of construction for carrying my invention into effect, these are 80 capable of variation and modification without departing from the spirit of the invention. I, therefore, do not wish to be limited to the precise details of construction set forth, but desire to avail myself of such 85 variations and modifications as come within the scope of the appended claims.

Having described my invention what I claim as new and desire to secure by Letters Patent is:

1. A device of the kind described comprising an insulating block having recesses in its outer side and an opening leading inwardly from each recess; a fixture connector embedded in said insulating block; a plurality of electric wire connectors embedded in said insulating block; each wire connector having a line wire socket and a fixture wire socket therein; and a binding screw threaded in each socket extending through an opening in said block and having its head disposed in one of the recesses in said block, substantially as described.

2. A device of the kind described comprising an annular insulating block having

recesses in its top side leading downwardly, recesses in its periphery and openings leading from said peripheral recesses to said downwardly extending recesses; electric wire connectors in said downwardly extending recesses; screws extending through said openings, threaded in said connectors and having their heads disposed in said peripheral recesses; and a fixture connector fitted in said block, substantially as described.

In testimony whereof I have signed my name to this specification in the presence of two subscribing witnesses.

HENRY P. McBRIDE.
